CLAIM

The ornamental design for a hanger clip, as shown and described.

DESCRIPTION

FIG. 1 is a perspective view of a hanger clip showing my new design;

FIG. 2 is a front plan view;

FIG. 3 is a back plan view;

FIG. 4 is a right side elevational view;

FIG. 5 is a left side elevational view;

FIG. 6 is a top plan view; and,

FIG. 7 is a bottom plan view.

The broken lines shown in the drawings represent portions of the hanger clip that form no part of the claimed design. The broken line(s) which define the bounds of the claimed design form no part thereof.
